US0D1059812S

(12) **United States Design Patent** (10) Patent No.: **US D1,059,812 S**
(45) Date of Patent: ** Feb. 4, 2025

(54) **BACKPACK**

(71) Applicant: **Samsonite IP Holdings S.a r.l.**,
Luxembourg (LU)

(72) Inventor: **Giorgio Michieli**, Lissone (IT)

(73) Assignee: **Samsonite IP Holdings S.a r.l.**,
Luxembourg (LU)

(**) Term: **15 Years**

(21) Appl. No.: **29/862,669**

(22) Filed: **Dec. 12, 2022**

(30) **Foreign Application Priority Data**

Jul. 1, 2022 (EM) 009074198-0003

(51) **LOC (15) Cl.** **03-01**

(52) **U.S. Cl.**

USPC **D3/217**
